PUSH BUTTON SWITCH

Albert Gibson, Chicago, Ill.

Application May 25, 1939, Serial No. 275,745

1 Claim. (Cl. 200—4)

The present invention relates to new and useful improvements in push button switches and has for its primary object to provide, in a manner as hereinafter set forth, a device of this character which is adapted to control a large number of door bells or other electric signals, the invention being particularly useful in apartment and other buildings.

Another very important object of the invention is to provide a multiple push button switch of the aforementioned character which may be expeditiously set or adjusted for ringing the desired bell.

Other objects of the invention are to provide a push button switch of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a push button switch constructed in accordance with the present invention.

Figure 2 is a plan view thereof.

Figure 3 is a sectional view, taken substantially on the line 3—3 of Fig. 1.

Figure 4 is a sectional view, taken substantially on the line 4—4 of Fig. 3.

Figure 5 is a sectional view, taken substantially on the line 5—5 of Fig. 3.

Figure 6 is a detail view in perspective of the disk supporting bracket.

Referring now to the drawings in detail, it will be seen that the embodiment of the invention which has been illustrated comprises a circular plate 1 of suitable insulating material which is adapted to be mounted on a wall or other support. Mounted centrally in the plate 1 is what may be referred to as a main contact 2 for connection with a suitable source of electric current. Encircling the contact 2 in spaced, concentric relation thereto is an endless series of contacts 3 to be electrically connected with the bells to be controlled by the switch.

Mounted on the marginal portion of the circular plate 1 is a metallic ring 4 having an annular flange 5 on its periphery engaged with the periphery of said plate 1. The ring 4 and the plate 1 are apertured to accommodate secur-

ing screws 6 for mounting the assembly on a wall or other support. The ring 4 includes an offset inner marginal portion 7 having therein an opening or window 8 the purpose of which will be presently set forth. 5

Rotatably mounted on the plate 1 is an annular casing 9 of suitable metal comprising a substantially conical outer portion 10. The inner end of the casing 9 is provided with an external flange 11 which is engaged beneath the offset 10 portion 7 of the retaining ring 4, thus rotatably securing said casing in position. The flange 11 is numbered, as at 12, said numbers 12 corresponding to the contacts 3 and being adapted to be brought into registry with the opening or 15 window 8.

The outer end of the casing 9 has formed therein an opening in which a push button 13 is slidably mounted. Extending inwardly from the push button 13 is a stem 14 having a conductor arm 15 secured on its inner end portion by a nut 16. The inner end of the stem 14 is engageable with the center contact 2 and the outer end portion of the arm 15 is engageable with any of the contacts 3. 20

Extending inwardly from the outer end of the casing 9 is a neck 17 which encircles the push button 13 and which is provided, on its inner end, with an external flange 18. A flange 19 on the inner end of the push button 13 is engageable with the flange 18. Mounted on the neck 17 is a resilient wire bracket 23 comprising substantially U-shaped clamping arms 20 having mounted therebetween a disk 21. The bight portions of the substantially U-shaped arms 20 are 35 bent inwardly in a manner to provide retaining hooks 24 engaged beneath the disk 21. The resilient bracket 23 further includes outwardly bowed connecting bars 25 adapted to receive therebetween and clamp the flanged neck 17 40 for firmly but removably securing said bracket thereon. The stem 14 passes slidably through an opening provided therefor in the disk 21. The disk 21 constitutes a seat for a coil spring 22 which encircles the stem 14 and which is engaged with the button 13 for yieldingly pushing said button outwardly. 45

It is thought that the operation of the invention will be readily apparent from a consideration of the foregoing. The switch is normally 50 maintained in open position by the coil spring 22 which yieldingly holds the conductor arm 15 away from the contacts 2 and 3, as shown to advantage in Fig. 3 of the drawings. To operate the switch, the casing 9 is rotated to bring the 55

desired number 12 into view in the opening 8 thereby positioning the arm 15 over the corresponding contact 3. The button 13 is then pushed inwardly against the tension of the coil spring 22 for bridging the contact 2 and the desired contact 3. Of course, when the button 13 is released the switch is immediately opened again by the spring 22. It will thus be seen that by simply rotating the casing 9 to the desired position any one of a number of door bells or other electric signals may be energized. If desired, the contacts 3 may be identified by numbers or letters, or both, on the plate 1 to facilitate installation, inspection, the making of 15 repairs, etc.

It is believed that the many advantages of a push button switch constructed in accordance with the present invention will be readily understood and although a preferred embodiment 20 of the device is as illustrated and described, it is to be understood that changes in the details of construction and in the combination and arrangement of parts may be resorted to which will fall within the scope of the invention as 25 claimed.

What is claimed is:

A switch including a plate, a plurality of contacts mounted on said plate, a casing rotatably mounted on the plate and having an opening therein, a flanged neck on the casing extending 5 inwardly from the opening, a resilient wire bracket removably mounted on the neck, said bracket comprising substantially U-shaped clamping arms, the bight portions of said substantially U-shaped arms being bent inwardly 10 and constituting retaining hooks, said bracket further including outwardly bowed connecting bars engaged with the neck, a disk mounted between the arms of the bracket and engaged on the hooks, a button extending slidably through 15 the opening and the neck, a stem fixed to said button and extending slidably through the disk, an arm mounted on said stem and engageable selectively with the contacts for electrically connecting said contacts, and a coil spring encircling the stem and having one end engaged with the disk and its other end engaged with the button for disengaging the arm from the contacts. 20

ALBERT GIBSON. 25
